UNITED STATES PATENT OFFICE.

GUSTAV A. HASSEL, OF MCKEESPORT, PENNSYLVANIA, ASSIGNOR TO
PITTSBURGH EQUIPMENT COMPANY, OF PITTSBURG, PENNSYLVANIA, A CORPORATION OF PENNSYLVANIA.

METALLIC BOLSTER.

No. 853,584.

Specification of Letters Patent.

Patented May 14, 1907.

Application filed March 2, 1907. Serial No. 360,140.

To all whom it may concern:

Be it known that I, GUSTAV A. HASSEL, of McKeesport, in the county of Allegheny and State of Pennsylvania, have invented certain new and useful Improvements in Metallic Bolsters, of which the following is a specification.

The prime object of the present invention is to provide a new and improved metallic bolster for cars.

To this end my invention consists of a metallic-bolster, in the novel features of construction and in the combination of parts all as fully hereinafter described and claimed.

In the accompanying drawing, which illustrates applications of my invention, Figure 1 is a central vertical sectional view of a portion of a bolster embodying my invention; Fig. 2 a similar view of the compression and tension-members before the end-member is applied thereto; Figs. 3 and 4 plan views of bolster showing slightly modified forms; Fig. 5 a view similar to Fig. 1 showing a modification; Fig. 6 a sectional view taken on line 5—5 of Fig. 3; and Fig. 7 a sectional view taken on line 7—7 of Fig. 4.

Referring to the drawing, 1 designates a compression-member of the bolster; as illustrated and as preferred this member is of channel-form, but other forms may be employed for the compression-member. Located near each end of this member I provide a plurality of openings or holes 2 made in the web of the member or between its flanges 3. I have shown three sets of openings 2, but the number of and form of openings may be varied.

The tension-member 4 of the bolster preferably consists of a flat plate suitably bent or cambered and provided with a plurality of openings 5 located near each end thereof and corresponding to the openings 2 of the compression-member. The openings 5 are so disposed as to register with the openings 2 when the compression and tension-members are assembled. The respective ends of the two members are securely and permanently held in end-members or castings 6 cast on the ends of the compression and tension-members.

In the manufacture of my bolsters, the ends of the compression and tension-members with their respective openings in register with one another are introduced into molds

and then molten metal is poured to form the 55 end-members. This molten metal enters the openings 2 and 5 and also surrounds and embeds the ends of both the compression and tension-members thereby permanently securing said ends within the end-members 60 without the necessity of employing independent rivets or other separate parts for connecting the end-members and the ends of the compression and tension-members.

A characteristic and important feature of 65 construction in the present invention is the location of the side-bearing-members 7 on the end-members of the bolster. As shown, a side-bearing-member is formed integral with each of the end-members. By placing 70 the side-bearing-members on the strong end-members the severe blows to which the said bearing-members are subjected in practice are transferred from the compression-member to the end-members thereby greatly relieving the compression-member of the bolster.

What I claim is:

1. A metallic-bolster comprising a compression-member provided with a plurality 80 of openings near each end, a tension-member provided with a plurality of openings corresponding to the openings of the compression-member and arranged to register therewith, and an end-member formed with a side-bearing-member cast on the ends of the compression and tension-members having its metal entering the registered openings of the compression and tension-members.

2. A metallic-bolster comprising a compression-member of channel-form having openings located near each end and between its flanges, a tension-member having openings corresponding to the openings of the compression-member and arranged to register therewith, and an end-member formed with a side-bearing-member cast on the ends of the compression and tension-members having its metal entering the registered openings of the compression and tension-members.

3. A metallic-bolster comprising a compression-member, a tension-member, and an end-member casting formed with a side-bearing-member cast on the ends of the compression and tension-members.

4. A metallic-bolster comprising a compression-member, provided with an opening near each end, a tension-member provided

with an opening near each end corresponding to the openings of the compression-member and arranged to register therewith, and an end-member casting formed with a side-bearing-member cast on the ends of the compression and tension-members and having its metal entering the registered openings thereof.

In testimony whereof I affix my signature in presence of two witnesses.

GUSTAV A. HASSEL.
